UNITED STATES PATENT OFFICE.

CHESTER R. PIEPER, OF LA CROSSE, WISCONSIN.

HAIR NET.

Application filed March 8, 1922. Serial No. 541,983.

To all whom it may concern:

Be it known that I, CHESTER R. PIEPER, a citizen of the United States, and a resident of La Crosse, in the county of La Crosse 5 and State of Wisconsin, have invented a new and useful Improvement in Hair Nets, of which the following is a full, clear, and exact description.

My invention relates to hair nets, and it 10 consists in the combinations, constructions, and arrangements herein described and claimed.

A further object of my invention is to provide a process of manufacturing a spherical-shaped hair net by means of a plastic material, such as cellulose, which is passed through a molding device having a flat or curved surface.

A further object of my invention is to 20 provide a hair net of the character described which may be made of a cellulose material and colored to match various shades of hair.

A further object of my invention is to provide a hair net of the character described 25 in which knots, sharp bends, and frayed ends are entirely obviated.

A further object of my invention is to provide a hair net and a process for constructing the same, in which the hair net is 30 absolutely free from any unsanitary conditions, such as might arise by the use of human hair if not treated.

A further object of my invention is to 35 provide a hair net and a process for manufacturing the same which reduces the cost of the article to a minimum.

Other objects and advantages will appear in the following specification, and the novel features of the invention will be particularly pointed out in the appended claims.

My invention is illustrated in the accompanying drawing, forming part of this application, in which—

Figure 1 is a top plan view of the hair net as it leaves the molding device,

Figure 2 is a sectional view of the hair net in operative position,

Figure 3 is a sectional view of the molding device in which the hair net is formed, and

Figure 4 is a partial elevation of the mechanism shown in Figure 3.

In carrying out my invention, I make use 55 of a cellulose compound which may be brought to a soft plastic state for working.

This compound may be colored with dyes to match the shade of various hues of hair. When the compound has been properly colored, and is brought to a plastic state, it is passed between a pair of rollers 1 and 2, 60 which rollers are in contact with one another at 3. The roller 1 has depressions upon its surface forming the pattern shown in Figure 1, which pattern is in exact accordance to the plane view of the hair net before it is 65 extended for use.

With reference to Figure 1, it will be noted that the hair net, as formed by the depressions on the roller 1, consists of an outer band 4 which is relatively heavy. This band 70 4 serves as a means for confining the hair net to the head when applied to the wearer. A plurality of irregular concentric rings 5, 6, 7, 8 and 9 are disposed within the band 4 and are connected one to another by means 75 of transverse radially extending threads 11. The real circumference of the ring 5 is greater than that of the band 4. This is clearly shown in Figure 2 where a hair net is shown extended and ready for use. The real 80 circumferences of the rings 7, 8, and 9 are less than the band 4 and gradually diminish as they approach the center or top of the hair net.

When the net, as shown in Figure 1, is extended, that is, when the bands 6, 7, 8, and 9 are pushed upwardly, the whole will assume an irregular spherical shape, and will have the general appearance of the ordinary 85 type of cap hair net.

In forming the hair net as previously described, the plastic material 12 is placed above the moving rollers 1 and 2. In this case, the rollers 1 and 2 move toward each other, and the material 12 will be drawn 90 into the depressions 13 on the roller 1. The roller 2 will, because it is in close contact with the roller 1, prevent any material from entering between the rollers at any other points than the depressions 13 therein.

The hair net, as shown in Figure 1, will therefore drop from beneath the rollers 1 and 2, and will at this time be in a substantially flat shape. When dry, the hair net is 95 ready for use.

While I here describe the use of moving rollers to form the hair net, it should be understood that a flat matrix would do equally as well, or any other kind of dye casting machine. One of the important advantages in 110

this process for manufacturing the hair net is that there is no wash material, since all of the material is consumed in the actual formation of the net. This could not be possible were the hair net made of fabricated thread or hair, which process is not only more expensive, but requires a great deal more time.

I claim:

- 10 1. A hair net of the character described comprising a plurality of convoluted endless strands disposed concentric to one another and connected one to another by integral strands when said hair net is disposed in a flat plane, said convoluted strands arranged to be straightened to cause said hair net to assume the shape of an irregular hemi-
- 15

sphere, said convoluted strands and said connecting strands being composed of a cellulosic substance.

2. A hair net of the character described comprising a plurality of convoluted endless strands disposed concentric to one another and connected one to another by integral strands when said hair net is disposed in a flat plane, said convoluted strands arranged to be straightened to cause said hair net to assume the shape of an irregular hemisphere, said convoluted strands and said connecting strands being composed of a cellulose substance, and dyed to resemble a predetermined shade of human hair.

CHESTER R. PIEPER.
